UNITED STATES PATENT OFFICE.

WILLIAM P. ROBERTSON, OF NEW YORK, N. Y., ASSIGNOR OF ONE-HALF TO E. W. HAMMOND, OF NEW YORK, N. Y., AND ONE-THIRD TO THE WATERTOWN MANUFACTURING COMPANY, OF WATERTOWN, CONNECTICUT, A CORPORATION OF CONNECTICUT.

ATTACHMENT PLUG.

Application filed September 30, 1921. Serial No. 504,503.

To all whom it may concern:

Be it known that I, WILLIAM P. ROBERTSON, a citizen of the United States, and a resident of the borough of Manhattan, city, 5 county, and State of New York, have invented certain new and useful Improvements in Attachment Plugs, of which the following is a specification.

My invention relates to a type of electrical 10 devices commonly known as attachment plugs which are usually attached to the end of a flexible conductor for the purpose of connecting an electrical device, such as a lamp, to a source of electricity.

15 An object of my invention is the provision of a device of this character which may be readily attached to the usual socket or other connecting device without the necessity however, of twisting the plug whereby 20 twisting of the conductor attached to the plug is avoided.

25 A further object of my invention is the provision of a plug of the character designated wherein a central contact and an outer contact are provided, means being carried by the plug for forcing the outer contact into firm engagement with the socket or other device with which the plug is used.

30 A further object of my invention is the provision of means manually operable for locking the plug in place when in use.

35 A further object of my invention is the provision of an attachment plug wherein a yielding central contact is provided whereby good contact will always be assured.

40 A still further object of my invention is the provision of an attachment plug which is simple in construction and therefore easy to manufacture and assemble and wherein the working parts are reduced to a minimum.

45 In the accompanying drawings wherein I have illustrated an embodiment of my invention,—

Fig. 1 represents my improved plug in part sectional elevation, showing the same in place in an ordinary socket;

Fig. 2 is a view taken substantially on the line 2—2 of Fig. 1, looking in the direction of the arrows;

Fig. 3 is a section taken on the line 3—3 of Fig. 2;

Fig. 4 is a front elevation of my improved plug with the screw cap with which the

55 plug is provided, removed and the front part of the plug broken away to show the operating mechanism of the locking means for the plug and the means for forcing the outer contact of the plug into good contact with the side of a socket;

60 Fig. 5 is an elevation of the locking means; and

Fig. 6 is a side elevation of Fig. 5.

65 It is to be understood in connection with this invention that the means employed for forcing the outer contact of the plug into good contact with the side of a socket or other device with which the plug may be employed, also locks the plug in place in said device, so that the member shown in Fig. 5 70 has a double function.

75 Referring to the drawings in detail, 1 designates a block of insulation which may be referred to as a base for my improved plug. This insulating base is cut away as indicated at 2 for the reception of a locking device 3 which in the present instance is also of insulation and which locking device, as above indicated, functions to force the outer contact of my improved plug into engagement with the side walls of a socket. The cut away portion 2 of the base 1 is, as indicated in Fig. 4, extended laterally at 4 and 5 so as to form guides 6 and 7 for the member 3. Surrounding the base 1 and the member 3 is an outer contact 8 of thin brass, for 80 example, and which outer contact may be crimped as indicated at 9 and 10 to hold the same in place on the base 1. The contact 8 is cut out at 11 so that the outer face of the member 3 may extend therethrough. Carried within the base 1 and secured thereto in any suitable manner is a spring 12, this spring backing up the member 3 and always urging the same outwardly to force a portion of the face thereof beyond the surface of the contact 8 as plainly indicated in Fig. 3. This projecting portion of the member 3

85 I have designated 13. It may here be remarked that it is unnecessary to make the member 3 entirely of insulation, the insulation being provided merely for the purpose of closing a contact through the plug by means of the member 3. It would be sufficient for my purpose, therefore, to insulate the member 3 from the contact 8.

90 It will be seen from Fig. 3 that the member 3 slides on the guideways 6 and 7 already

65

referred to, radially with respect to the base 1 as distinguished from a pivotal movement. In order that the member 3 may be easily manipulated, that is to say forced inwardly 5 against the action of the spring 12, I provide a projection 14 thereon at the upper end thereof and which projection is always accessible from the exterior of the plug. By having the member 3 slidably mounted as 10 distinguished from a pivotal mounting, the movement of the member 3 necessary to carry it out of operative position, is lessened. The base 1 is reduced at 15, this reduced portion being screw-threaded for the reception 15 of an insulated cap or ring 16 through which the conductors 17 are led.

The outer contact 8 has an upwardly extending contracted portion 8' secured to a plate 18 carrying the terminal binding screw 20 19. Passing centrally through the base 1 is a central contact comprising a rod 20 carrying at the lower end thereof a screw-threaded member 21 constituting the contact proper, this member being adjustable on the 25 rod 20 and sliding in a guideway 22 in the base 1. Pressing against the upper end of the rod 20 is a spring 23 set into the top of the base 1, the other end of this spring being constantly in engagement with a conducting 30 plate 24 through which passes a binding post 25 to which the other conductor of the pair of conductors 17 is connected. In order that the connections made at the binding posts 19 and 25 may be adequately protected 35 I provide between them an upwardly extending insulated member 26.

The socket illustrated and one with which my improved plug may be employed is of the usual construction, comprising a screw-threaded inner wall or tube 27 constituting 40 a contact, an insulated base 28 and a central contact 29.

From the foregoing it will be seen that with my plug in place in the socket electrical 45 connection is established from any suitable source of supply by way of conductor 30, conducting element 31, metal tube contact 27 of the socket, outer contact 8 of my plug, plate 18, terminal 19, one conductor of the 50 pair of conductors 17, through the device which it may be desired to operate, such as a lamp for example, back through the other conductor of the pair 17, terminal 25, plate 24, spring 23, rod 20, central contact 55 21, contact member 29 of the socket, plate 32, to the other conductor 33.

To insert my improved plug in its socket it is merely necessary to press inwardly on the projection 14 of the insulated member 3 60 to force the member inwardly radially with respect to the base 1 thereby carrying the face 13 of the member inwardly beyond the face of the outer contact 8 or flush therewith so that the plug may be readily inserted 65 in the socket. Upon releasing the pressure

on the projection 14 the member 3 will be moved outwardly under the action of the spring 12 to force the plug laterally bodily, carrying the outer contact 8 into firm engagement with the wall member or contact 70 27 of the socket. The member 3 will also, due to its engagement with the wall of the socket, maintain the plug in place therein. While I have shown the projecting portion 75 13 of the member 3 screw-threaded to cooperate with the screw-threaded wall 27 of the socket, it will be understood, of course, that this is not necessary, this showing having been made by way of illustration only. When it is desired to remove the plug from the socket by applying pressure at 14 the member 3 may be forced inwardly again to carry the portion 13 thereof out of contact with the wall of the socket whereby the plug may be pulled outwardly. 80 85

From the foregoing it will be seen that I have provided an attachment plug which may be inserted into a socket and locked in place therein without the necessity of rotation of the plug at all whereby twisting of the conductors attached to the plug is avoided and whereby the plug may be inserted in place instantly. 90

It will be seen also that to remove the plug it is also unnecessary to rotate the 95 same.

It will be apparent also from the foregoing that I have provided a plug embodying a contact and means carried by the plug for forcing this contact into firm engagement with the wall of a socket or other device with which it is desired to employ the plug by causing a bodily movement of the plug. 100

It will be apparent also that I have provided a plug wherein locking means carried thereby is employed which locking means is movable independently of a contact constituting a part of the plug and which locking means is in itself insulated, constituting no part of an electrical circuit when the device is in use. 105 110

While I have illustrated and described a specific embodiment of my invention, it is to be understood that I am not to be limited thereto inasmuch as various changes may be made in the details of construction and arrangement of parts within the purview of my invention. 115

It is to be further understood that if desired the contact 8 carried by the plug could be screw-threaded to conform to the screw-threads on the contact member 27 of the socket. 120

It is obvious, furthermore, that if desired the member 3 could be mounted on the socket instead of upon the plug, the purpose of this member being two-fold as set out above, to wit: for moving the plug bodily so as to bring the contact carried thereby 125 130

into engagement with a contact-carrying device such as a socket, and to hold the plug in place therein.

What I claim is:

- 5 An attachment plug comprising a metallic cylindrical shell having an annular flange at one end thereof, a body portion of insulating material adapted to lie within said shell, a shoulder portion on said body portion
10 adapted to engage the flange on the shell, an ear connected to the shell and turned over to bear against the rear face of said body portion to hold the body portion within the shell, said shell and body portion
15 being provided with a recess, the shell over-
- hanging the recess in the body portion thereof of defining flanges, an element disposed within said recess, resilient means back of said element within said recess tending to move said element out of said recess, a plurality of screw threaded formations on the exterior surface of the element, and shoulders on the element adapted to engage with the flange portions to prevent the element from being moved completely out of said recess by said resilient means. 20 25

This specification signed this 29th day of Sept., 1921.

WILLIAM P. ROBERTSON.
